DISH DRAINER BASKET

George S. Chapman, 1712 Park Blvd., Erlton, N.J.

Filed Dec. 6, 1961, Ser. No. 67,818

Term of patent 14 years

(Cl. D44—29)

FIG. 1 is a perspective view of a dish drainer basket showing my new design.

FIG. 2 is an end elevational view thereof.

The characteristic feature of my design resides in the open wirework sides having a plurality of spaced vertical wires, a wire of substantially sinuous configuration having spaced inverted V-shaped portions positioned between certain of said vertical wires, and a plurality of relatively short wires extending from the bottom of the device upwardly and terminating below and in spaced relation to the respective apices of said V-shaped portions.

I claim:

The ornamental design for a dish drainer basket, substantially as shown and described.
